UNITED STATES PATENT OFFICE.

ROBERT E. BAKER, OF CLEVELAND HEIGHTS, OHIO.

STORAGE BIN.

Application filed April 2, 1925. Serial No. 20,042.

My invention relates to storage bins used for holding large quantities of heavy material such as coal, iron ore or the like, and such as, for example, are shown and described in U. S. Patents Numbers 1,338,482 and 1,338,483 issued to me April 27th, 1920.

In a bin such as is shown in either of said patents, the bottom portion thereof is provided with a plurality of reinforcing or stiffening diaphragms or partitions which divide the storage space in such portion into a plurality of laterally arranged compartments. These partitions I have found serve as obstructions which frequently cause the 10 contents of the bin to form fixed arches in and over the said compartments, and impede or stop the required downward flow of the material, when it is desired to discharge same by gravity from the bottom of the bin.

15 The object of my present invention is to provide a bin structure in which said arching and consequent obstruction to flow of material by gravity, is eliminated, and may be applied to either the flexible-sided type 20 of bin shown in said patents, or the rigid-sided type of bins which is sometimes employed.

This object I attain by providing reinforcing or stiffening means for the bottom 30 portion of the bin of such a character as will not include said previously described partitions and hence their attendant undesirable effect. This I accomplish by securing exteriorly located stiffening means to the 35 bottom portion of the bin, which are so placed as to counteract the tendency of the front and rear walls of such portion, to bulge outwardly.

The annexed drawings and the following 40 description set forth in detail certain means embodying my invention, the disclosed means, however, constituting but one of the various mechanical forms in which the principle of the invention may be employed.

45 In said annexed drawings:

Figure 1 represents a vertical transverse section of a bin to which my present invention has been applied, the section being taken in the plane indicated by the line I—I, Figures 2 and 5.

50 Fig. 2 represents a front elevation of the lower portion of said bin and upon a somewhat enlarged scale.

Fig. 3 represents an end elevation taken 55 upon the plane indicated by line III—III,

Fig. 2, and viewed in the direction indicated by the arrows.

Fig. 4 represents a section taken upon the plane indicated by line IV—IV, Fig. 2, and viewed in the direction indicated by the arrows.

Fig. 5 represents a section taken upon the planes indicated by lines V—V, Fig. 4, and viewed in the direction indicated by the arrows.

Fig. 6 represents a fragmentary elevation taken upon the plane indicated by line VI—VI, Fig. 4, and viewed in the direction indicated by the arrows.

Fig. 7 represents a front elevation of the bottom portion of a modified form of bin embodying a feature of my invention.

Fig. 8 represents a section taken upon the plane indicated by line VIII—VIII, Fig. 7.

Fig. 9 represents an end elevation of such modified form of bin bottom.

My present invention, in the form illustrated by Figs. 1 to 6 inclusive, is shown to be applied to the suspended flexible-sided type of bin shown in my above-mentioned 80 patents, and in which the front and rear walls converge downwardly as shown, and which is provided with the vertical end walls 1—1.

The front wall consists of a main or upper 85 portion 2 and a bottom portion 3. The latter terminates a distance above the lower end of the bin to form a longitudinal rectangular discharge opening running the entire length between the two end walls 1—1, as shown in Figs. 1, 2 and 4. This opening is controlled by a multiplicity of gates 4 laterally juxtaposed as will be hereinafter further described.

The back wall consists of a main or upper 95 portion 5 and a bottom portion 6.

That portion of the end walls 1—1 which forms the end walls of the bottom portion of the bin, extends beyond the front and rear walls of such portion as shown in Fig. 3. 100 For the purposes of convenience and assembly these end wall portions are made of separate plates 7—7 alined with the lower ends of the main end plates 8—8 by means of riveted flat bars 9—9 as shown in Figs. 2 105 and 3.

Extending between the end plates 7—7, upon the outside of the front and back walls and secured respectively thereto by means of angles 10'—10', are two horizontal sup- 110

porting beams 10—10, of I-beam section preferably, the webs of which extend at right angles to said walls, as shown in Figs. 3 and 4.

5 The upper part of both the rear and front extensions of the end plates 7—7 are made of a width substantially equal to the depth of the beams 10—10.

Also for convenience of assembly and 10 pair, the bottom wall portions 3 and 6 are each made of a separate plate, the lower ends of plates 2 and 5 being secured to the upper part of the inner flanges 11—11 of the beams 10—10, and the upper ends of the 15 plates 3 and 6 being secured to the lower part of such flanges by means such as the rivets shown, Figs. 2 and 3.

Intermediately of the gates 4 (between each adjacent pair as illustrated) are a 20 plurality of tension members 12, made of plate and in contact with the front plate 3. Each of these members is of a shape and size similar to that of the extended portion of the end plates 7—7, on the front of the bin, 25 and has its upper end secured to the lower side of the front beam 10 by means of suitable angles 12'—12', Fig. 4.

The front plate 3 may also be secured to the members 12 by means of angles 3', as 30 shown in Figs. 2 and 4.

Upon the lower end portion of the extension of end plates 7—7 and the member 12, are secured longitudinally alined brackets 13, which support a rod 14 upon which the 35 gates 4 are pivotally mounted, as shown in Figs. 2 and 3. Each gate may be separately actuated through the medium of a suitable handle 4' attached thereto.

Each member 12 has its lower rear end 40 portion extending backwardly through a slot 15, Figs. 5 and 6, cut in the bottom of the back plate 6, and each such rearwardly projecting portion of said members, is secured to the bottom of a rear tension member 16, of channel section, by means of an angle 17, Fig. 6.

These members 16 lie against the rear plate 6 and each has its upper end secured to the lower side of the rear supporting beam 10 by means of angles 18, Figs. 4 and 5.

The lower extremity of the bottom portion of the bin is reinforced by a horizontal angle bar 19 secured to the lower end of the 55 rear plate 6 and to the channel member 16, by means of angles 20, Figs. 4 and 5, the lower ends of members 12 being cut out for that purpose as shown.

It will be seen from the above described 60 arrangement that each connected set of tension members 12 and 16 forms a saddle or sling which is supported at its upper end by the two beams 10—10, the latter being supported by the upper part of the bin, 65 such slings reinforcing the two plates 2 and

6 and counteracting their tendency to bulge outwardly when the force due to the weight of the load in the bin, is applied thereto. These reinforcing members being, as described, located entirely upon the outside, 70 the inner storage space of the bottom portion of the bin is free and unobstructed so that the arching previously referred to is eliminated or at least minimized.

Figs. 7, 8 and 9 illustrate a feature of my 75 invention as applied to a bin of the suspended type and in which the discharge openings are placed centrally at the bottom.

In this form the front and back walls, 3 and 6 respectively, of the bottom portion 80 are each reinforced by longitudinal horizontal I-beams 21, the uppermost of which, 21', are secured to the lower end-portion of the main front and back walls, 2 and 5 respectively, the end walls 7—7 being alined 85 with the end walls 1—1, as in the first described structure.

As shown, these I-beams are all secured to the exterior of walls 3 and 6 and their ends secured to the end-walls 7—7, by means 90 of suitable angles 22, said end walls being extended front and rear for that purpose, as shown in Fig. 9.

This modified form, therefore, has its 95 front and rear walls exteriorly reinforced to prevent them from bulging outwardly, but the reinforcing means are not suspended or of sling form as in the first-described form of my invention.

It will also be apparent to those skilled in 100 the art, that the described sling method of reinforcement may be applied to a bin having its discharge openings centrally placed.

Either type of reinforcement may be used 105 in connection with a bin of the form shown in Figs. 7 to 9, but the sling-type of reinforcement is particularly suitable to the type of bin, shown in Figs. 1 to 6, and in which the openings are in the side rather than centrally at the bottom, all as will be 110 understood by those familiar with the art.

What I claim is:

1. A storage bin formed with an upper portion and a rigid bottom portion having 115 front and rear walls, and external reinforcing means for said front and rear walls suspended from said upper portion.

2. A storage bin comprising an upper portion having flexible, suspended front and rear walls, and a rigid bottom portion having front and rear walls, and means suspended from said bin and adapted to externally reinforce said last-mentioned front and rear walls against outward bulging. 120

3. A storage bin having upper main front 125 and rear walls and a bottom portion having front and rear walls, said bottom portion being provided with reinforcing means suspended from the main front and rear walls of said bin and exteriorly reinforcing 130

the front and rear walls of said bottom portion.

4. A storage bin having front and rear walls having a sling hung from the lower portion of the front and rear walls, said bin having a bottom portion with end, front and rear walls, said sling acting as a stiffening member for the front and rear walls of the bottom portion and intermediately of the end walls thereof.

5. A storage bin having an upper portion and a bottom portion including two end walls, front and rear walls, and a multiplicity of slings supported by the upper portion 15 of the bin, located upon the outside of said bottom portion and supporting the said front and rear walls.

6. A storage bin having main end, front and rear walls and a bottom portion having 20 end, front and rear walls in continuation of said main walls; front and rear longitudinal members secured respectively to the bottom of the said main front and rear walls and having the tops respectively of said bottom 25 front and rear walls secured thereto; and a sling hung from said longitudinal members and supporting the front and rear walls of said bottom portion intermediately of its ends.

30 7. A storage bin having main end, front and rear walls and a bottom portion having end, front and rear walls; two longitudinal members located at the back and front respectively of the bin and having their ends secured to the end walls of the bottom portion of the bin and being also secured to the bottoms of the main front and rear walls; the upper ends of the front and rear walls of the bottom portion of the bin being secured to said members; and a sling hung 35 from said members supporting the front and back walls of said bottom portion intermediately of the ends thereof.

8. A storage bin of the suspended type comprising end, front and rear walls forming upper and lower portions, said bin being provided with means for externally reinforcing the lower portion throughout its vertical length; such means being suspended 45 from the upper portion of said bin. 50

9. A storage bin of the suspended type comprising end, front and rear walls forming upper and lower portions, said bin having a rectangular horizontal cross-section and said bottom portion being externally reinforced to make it rigid. 55

10. A storage bin of the suspended type comprising end, front and rear walls forming upper and lower portions, said bin having a rectangular horizontal cross-section 60 and having its bottom portion provided with externally placed reinforcement; the latter being suspended from the front and rear walls of said upper portion.

11. A storage bin having a bottom portion 65 provided with a single storage space, said bin portion being formed with a plurality of discharge openings; and a plurality of external reinforcing members for said bin portion extending transversely of the bin 70 and disposed respectively intermediate adjacent discharge openings.

12. A storage bin having a bottom portion provided with end, front and rear walls forming a single longitudinal storage space, 75 said bin portion being formed with a plurality of discharge openings; and a plurality of exteriorly located slings for supporting the front and rear walls of said bottom portion, said slings extending transversely of 80 said bin and being disposed respectively intermediate adjacent discharge openings.

Signed by me this 24th day of March, 1925.

ROBERT E. BAKER.
